UNITED STATES PATENT OFFICE

THEODORE WILLARD CASE, OF AUBURN, NEW YORK, ASSIGNOR TO CASE RESEARCH LABORATORY, INCORPORATED, OF AUBURN, NEW YORK, A CORPORATION OF NEW YORK

HIGH-FREQUENCY CONTROL OF A KERR CELL

Application filed July 23, 1928. Serial No. 294,868.

This invention relates to certain new and useful improvements in high frequency control of a cell capable of showing the Kerr effect and has many applications as for instance the production of a photographic record of light waves corresponding to sound wave variations, television, etc.

A primary object of the invention resides in the production of an effective apparatus embodying a high frequency carrier current modulated in any suitable way in accordance with the results desired and adapted to energize a cell capable of showing the Kerr effect in such a manner as to vary a beam of polarized light in accordance with the modulations impressed on the carrier current for the production, as for instance, of a photographic record of light waves corresponding to sound waves.

Other objects and advantages relate to the details of the structure and the form, arrangement and relation of the parts thereof, all as will more fully appear from the following description taken in connection with the accompanying drawing, in which:

The figure is a diagrammatic illustration of an embodiment of the invention.

For controlling the action of a cell capable of showing the Kerr effect, it is found desirable to utilize a modulated high frequency voltage of a frequency higher than the most rapid variations of the modulating wave so as not to cause mutual interference.

The value of this frequency may be as much higher than this lower limit as may be desirable.

When it is desired to utilize the invention to control the light transmission through the cell in accordance with a sound wave source, I utilize circuits corresponding quite closely to those employed in high quality radio telephone transmitting stations.

The drawing illustrates a circuit employing the constant current system of modulation, but I do not wish to be limited to any single system of high frequency current generation and modulation, as many other systems accomplishing the same results by other means are known and equally applicable to this invention.

As specifically illustrated in the drawing, sound waves are impressed upon a suitable microphone —1— which is connected in series with a battery —2— and the primary winding of the transformer —3—. This induces a potential in the secondary coil of transformer —3— which in turn varies the potential of the grid —5— with respect to the filament —6—. Battery —4— supplies a suitable biasing potential. Battery —9— serves to heat the filament —6— and battery —10— supplies the potential for the plate circuit of the electron tube —8— as well as for the plate circuit of electron tube —24—. Voltage variations impressed on the grid —5— cause corresponding fluctuations in the current flowing between the plate —7— and filament —6—.

These current fluctuations cause voltage fluctuations across the terminals of coil —11— which is wound so that its inductance is very high.

Coil —11— is common to the plate circuits of both electron tubes —8— and —24—, hence voltage variations produced by fluctuations of current flowing between —6— and —7— will cause effective voltage variations in the plate circuit of tube —24—. An oscillatory circuit consisting of coil —14— and condenser —15— is connected between the grid —21— and the filament —22— of the tube —24—. Battery —16— supplies a suitable biasing potential for the grid —21—. Coil —17— is coupled magnetically with coil —14— and wound in such a direction as to produce self-oscillation in the tube —24—.

Condenser —13— serves as a low impedance by-pass for the high frequency current around the coil —11—. Coil —12—, a high frequency choke, tends to keep the high frequency current out of the plate circuit of tube —8—.

The amplitude of the current generated in coils —14— and —17— will depend to a considerable extent upon the effective voltage in the plate circuit of tube —24—. This effective plate voltage will be the sum of the potential of the battery —10— and whatever voltage may be induced in coil —11— as the

result of the fluctuations in the plate current of tube —8—.

Due to the magnetic coupling between coil —18— and coils —14— and —17—, fluctuating high frequency voltages and currents will be induced in coil —18—.

Due to differences in the electrical characteristics of various types of cells showing the Kerr effect, I may choose to apply the high frequency voltages induced in the coil —18— directly to the terminals of the cell —25— by making a direct connection between the ends of the coil —18— and the two electrodes —26— and —27— respectively, or I may prefer to connect the battery —38— in series with one of the connecting wires joining the ends of coil —18— with the electrodes —26— and —27—.

With certain types of cell I may prefer to partially or completely rectify the voltages induced in coil —18— before applying them to the cell —25—. In this event a suitable rectifier would be associated with the output coil —18— and for this service a hot cathode vacuum tube rectifier has been found particularly suitable. A possible application is illustrated in the drawing on which —35— and —32— respectively represent the filament and plate of the hot cathode rectifier —33—. Battery —38— or its equivalent supplies current to the filament —35— to maintain it at the requisite temperature. Condenser —31— acts as a shunt across the leads to the cell and is used when desirable.

In accordance with the known operation of a cell capable of showing the Kerr effect, the voltage induced in coil —18— will control the light passing from source —30— through the crossed Nicol prisms —28— and —29—, or their equivalent.

The arrangement here illustrated in that connection comprises a straight line source of light such as an electric lamp —30— having a straight line filament extending parallel with the opening between the electrodes —26— and —27—. The light from this source passes through the Nicol polarizer —28— and is focussed by a lens or lens system —40— on the space between the electrodes —26— and —27—. The light emanating from the space between the electrodes then passes through the Nicol analyzer —29— and preferably through a lens or lens system —41— which focusses the light upon the photographic film —42—, an opaque barrier —43— being provided in front of the film and having an extremely narrow elongated slit through which the light passes to the film. Other means may, however, be relied upon for focussing a line of light of desired size upon the film or sensitized surface.

The condenser —19— is shown in shunt with coil —18— to tune the combination to resonance, and hence produce a maximum ef-

fect at the frequency of oscillation of the tube —24—. In some cases it is found that resonance tuning in coil —18— is not essential, and in such cases condenser —19— may be omitted and in some cases the natural or inherent capacitance of the coil —18— may be sufficient to tune it to resonance without the use of the condenser —19—.

When the invention is to be operated from other than a sound control source, as specifically illustrated in the drawing, as for instance when used in television, tele-photography and the like, for which uses it is well adapted, the circuit shown in the drawing need only be modified to allow the application of the necessary control voltages amplified to the proper degree by external amplifiers between grid —5— and the filament —6— of the electron tube —8—.

When the operation of the cell is to be controlled by radio or carrier current signals, as for instance in the recording of telephone signals, and in telephotography or television transmitted by radio or carrier current, the modulated oscillator will be located in the transmitting equipment and the modulated high frequency voltages received from the antenna or incoming lines may be applied directly to the coil —18— after having been amplified up to the proper level by any suitable amplifier system.

Altho I have shown and described a specific apparatus as constituting an embodiment of the invention I do not desire to restrict myself to the details of form, construction, arrangement or association of the parts thereof, as various changes and modifications may be made within the scope of the appended claims.

I claim:

1. In an apparatus of the class described, an electrical circuit including local means for producing a high frequency oscillating current, means for modulating said current in accordance with sound wave variations, means for rectifying said current, and a cell capable of showing the Kerr effect electrically associated with said circuit.

2. In an apparatus of the class described, an electrical circuit including local means for producing a high frequency oscillating current, means for modulating said current in accordance with sound wave variations, means for rectifying said current, a cell capable of showing the Kerr effect electrically associated with said circuit, means for causing polarized light to pass through said cell, and means for producing a visible record of light rays as varied by said cell.

3. In an apparatus of the class described, an electrical circuit including local means for producing high frequency oscillating current, means for modulating said circuit in accordance with sound wave variations, means for rectifying said current, a cell capable of show-

ing the Kerr effect and comprising a pair of spaced electrodes connected in said circuit, means for causing polarized light to pass through said cell and means for producing a photographic record of light rays as varied by said cell.

4. In an apparatus of the class described, an electrical circuit including local means for producing high frequency oscillating current, 10 means for modulating said current in accordance with sound wave variations, means for rectifying said current, a cell capable of showing the Kerr effect and comprising a pair of spaced electrodes connected in said circuit, 15 means for causing polarized light to pass through said cell and means for producing a visible record of light rays, as varied by said cell.

5. In an apparatus of the class described, 20 an electrical circuit including local means for producing a high frequency oscillating current, means for modulating said current in accordance with sound wave variations, means for rectifying said current, a cell capable of showing the Kerr effect and including an envelope having closely spaced electrodes therein, and means for conducting said rectified current to the electrodes of said cell.

6. In an apparatus of the class described, 25 an electrical circuit including means for producing locally a high frequency oscillating current, means for modulating said current by electrical variations locally applied, means for rectifying said current, a cell capable of 35 showing Kerr effect including closely spaced electrodes, and means for conducting said rectifying current to the electrodes of said cell.

In witness whereof I have hereunto set my
40 hand this 20th day of July, 1928.

THEODORE WILLARD CASE.
